COAL DISTRIBUTOR FOR STOKER RETORTS

Floyd R. Nelson, Rockford, Ill., assignor to Cotta
Transmission Corporation, Rockford, Ill., a
corporation of Illinois

Application January 2, 1936, Serial No. 57,153

5 Claims. (Cl. 110—45)

This invention relates to underfeed stokers, and has particular reference to means for evenly distributing the feeding of coal upwardly in the retort.

5 The principal object of my invention is to provide, in connection with the end of the feed screw projecting into the retort, a combination bearing and baffle arch in the retort extending over the projecting portion of the screw, the same having 10 an elongated opening therein over the screw and lengthwise with respect thereto, specially formed with relation to the screw and retort to cause even distribution of coal and at the same time the desired breadth of bearing surface, particu- 15 larly at the rearward end of the arch.

The invention is illustrated in the accompanying drawing, wherein—

Figure 1 is a plan view of a stoker retort showing the coal distributor arch;

20 Fig. 2 is a longitudinal section on the broken line 2—2 of Figure 1;

Fig. 3 is a sectional detail on the line 3—3 of Fig. 2, looking at the end of the arch, and

25 Fig. 4 is a similar view showing a modified or alternative construction.

Similar reference numerals are applied to corresponding parts throughout the views.

Referring to Figs. 1 to 3, 5 is the conduit extending forwardly from a coal hopper to the 30 retort 6 disposed under the firebox of the furnace, hot water heater, or boiler. The latter has tuyères 7 arranged in a rectangle over the retort, through which air to support combustion is discharged in a well known manner, the air being 35 delivered through an air duct (not shown) extending rearwardly from a blower in parallelism to the conduit 5. Dead plates 8 are disposed around the upper ends of the tuyères to complete the bottom of the firebox. Coal is fed into

40 the retort 6 through the conduit 5 by a screw 9. It is a problem to provide uniform distribution of this coal throughout the rectangular cross-sectional area of the retort so that the coal will not pile up at one point continually. Considerable 45 experimenting with different constructions disclosed a tendency for one construction to cause piling up at the far end of the retort and with another at the near end, and with still another at some intermediate point. This piling up I 50 found was due to a combination of conditions; the extent to which the feed screw projects into the retort was found to be an important factor in determining just where the greatest height would occur in relation to the ends of the retort. The 55 combination which I will now describe avoids the

difficulty of the coal piling up at one point and maintains an even top on the bed of coal at all feeds.

In accordance with my invention, an arch 10 is provided in the retort 6 extending over the 5 projecting end portion 11 of the screw 9 to serve both as a coal baffle and as a bearing for the screw, the inside surface 12 having the periphery of the thread of the screw arranged to slidably engage the same. An elongated opening 13 is 10 provided in the arch 10 extending lengthwise with respect to the screw. This opening is to allow coal to flow upwardly through the arch directly from the screw, and it is proportioned properly with relation to the dimensions of the 15 retort and diameter of the screw to make for uniform distribution of coal feed. The rear end of the opening is narrowed into a bottle neck, as indicated at 14, for two reasons, namely, to give increased bearing surface at the end of the screw 20 and also reduce the flow of coal through this portion of the arch to avoid piling up over the end of the screw adjacent the middle of the retort. The arch may be a separate plate having lugs 15 and 16 welded thereto or formed integral 25 therewith for fastening the same to the side walls of the retort as by bolts 17, or it may take the form of the arch shown at 10' in Fig. 4 integral with the side walls of the retort 6', the arch being in that case either welded in place or cast integral 30 with the retort. The bottom of the retort is formed, as best appears in Figs. 2 and 3, to provide a complementary bearing surface 18 for the end portion 11 of the feed screw under the arch 10, and to provide an upwardly inclined surface 35 19 rearwardly from the end of the screw. This inclined portion of the bottom of the retort plays an important part in the operation of the stoker, as will now be described.

In operation, it will be assumed that the retort 40 is empty at the outset. As the screw 9 turns, it will first discharge coal at the end thereof onto the upwardly sloping bottom 19. This continues until enough coal has been deposited beyond the screw to build up a certain resistance to further 45 discharge of coal from the end of the screw, whereupon there commences to be a discharge of coal upwardly through the opening 13 until the resistance to flow upwardly more than balances the resistance to flow from the end of the screw. 50 Then the discharge from the end of the screw is resumed until a greater resistance to flow at that point is developed by reason of the build-up in the depth of coal beyond the screw, whereupon coal is again discharged through the open- 55

ing 13, and so on. The retort fills up to an even depth, that is with the top thereof level with the tuyères throughout the length of the retort. If it were not for the arch 10 providing support for the projecting end portion 11 of the screw in the retort, this end portion might tend to flex away from the bottom of the retort, especially if finer coal particles were allowed to work in between the bottom of the retort and the periphery of the thread of the screw. The fact that the arch gives increased area of bearing surface adjacent the extremity of the screw minimizes wear and keeps the screw from flexing and binding. I am not prepared to offer an explanation as to why the reduction in the width of the opening 13 over the extremity of the screw, indicated at 14, results in even distribution, but can say that actual experimenting with different shaped openings showed conclusively that it eliminates or minimizes the tendency for the coal to pile up adjacent the center of the retort. In this connection, I would also state that the size of the opening 13—14 is also determined by experimenting, and its dimensions will differ for different sized retorts. In conclusion, it will be noticed that the end of the feed screw projects slightly beyond the end of the arch 10. This, too, is a condition which I have found affects the operation of the stoker. I have found that the best performance is obtained if the end of the screw is at least flush with the end of the arch or if it does not project more than, say three quarters of an inch from the end of the arch.

It is believed the foregoing description conveys a good understanding of the objects and advantages of my invention. The appended claims have been drawn with a view to covering all legitimate modifications and adaptations.

I claim:

1. As an article of manufacture, a stoker feed screw retort baffle comprising an elongated arcuate plate adapted to be placed concave side down over a feed screw in the inlet end of a stoker retort, said plate having a longitudinally extending opening provided therein reaching from one end thereof to a point near the other end, the opening being of uniform width for a portion of its length, the width representing a large fraction of the width of the plate, and said opening being narrowed abruptly to approximately half the first width and being of uniform narrow width the rest of its length.

2. As an article of manufacture, a stoker feed

screw retort baffle comprising an elongated arcuate plate adapted to be placed concave side down over a feed screw in the inlet end of a stoker retort, said plate having a longitudinally extending opening provided therein reaching from one end thereof to a point near the other end, the opening being symmetrical with respect to a longitudinal center line through said plate and being of a uniform width for approximately half its length and narrowed down to about half said width for the rest of its length.

3. In a screw type underfeed stoker, the combination of a retort having an inlet opening at one end thereof, a rotary screw for feeding coal through said opening into the retort, said screw projecting through said opening a certain distance into the retort representing a small fraction of the length of said retort, the bottom of the retort adjacent the inlet opening being conformed to provide bearing support for the lower half of the screw, and a substantially horizontally disposed combination screw bearing and coal discharge regulating baffle wall extending in an arc over the upper half only of an appreciable length of the projecting end of said screw in said retort, said wall having bearing engagement on the inside thereof with the periphery of the thread of the screw throughout a corresponding length of the screw, said wall having an opening provided therein over said screw for restricted discharge of coal upwardly there-through radially from the screw in addition to the unrestricted discharge of coal from the end of the screw.

4. A stoker as set forth in claim 3 wherein the opening provided in the baffle wall extends longitudinally thereof reaching from one end to a point near the other end, the opening being of uniform width for a portion of its length, the width representing a large fraction of the width of the wall, and said opening being narrowed abruptly to approximately half the first width and being of uniform narrow width the rest of its length.

5. A stoker as set forth in claim 3 wherein the opening in the baffle wall extends longitudinally thereof reaching from one end to a point near the other end, the opening being symmetrical with respect to a longitudinal center line through said wall and being of a uniform width for about half said width for the rest of its length.

FLOYD R. NELSON.
